(57) **CLAIM**

The ornamental design for a scent cartridge, as shown and described.

DESCRIPTION

FIG. 1 is front right side perspective view, from the top, of a scent cartridge showing an embodiment of our new design. FIG. 2 is a rear left side perspective view, from the bottom, thereof.

FIG. 3 is a top plan view thereof.

FIG. 4 is a bottom plan view thereof.

FIG. 5 is a right side elevational view thereof, the left side elevational view being a mirror image thereof.

FIG. 6 is a front elevational view thereof.

FIG. 7 is a rear elevational view thereof.

FIG. 8 is a front right side perspective view, from the top, of a scent cartridge showing another embodiment of our new design.

FIG. 9 is a rear left side perspective view, from the bottom, thereof.

FIG. 10 is a top plan view thereof.

FIG. 11 is a bottom plan view thereof.

FIG. 12 is a right side elevational view thereof, the left side elevational view being a mirror image thereof.

FIG. 13 is a front elevational view thereof; and,

FIG. 14 is a rear elevational view thereof.

Stippling and contour lines shown in the drawings are intended to represent the approximate three-dimensional contours of the design, and are not intended to indicate surface decoration. The broken lines in the figures are for illustrative purposes only and form no part of the claimed design.
